UNITED STATES PATENT OFFICE

2,051,957

LOCOMOTIVE TENDER

Nathan M. Lower, New York, N. Y., assignor to
The Standard Stoker Company, Incorporated,
a corporation of Delaware

Original application May 2, 1930, Serial No.
449,331. Divided and this application March
18, 1932, Serial No. 599,725

32 Claims. (Cl. 105—234)

This invention relates to locomotive tenders in which stoker mechanism is used and is a division of my copending application Serial Number 449,-331, filed May 2, 1930.

5 An object of the invention is the provision of a tender constructed to permit mounting the stoker drive mechanism in a compartment rearward of the stoker conveyor and trough.

Another object of the invention is the provision of a tender constructed to permit mounting the stoker drive mechanism comprising either gearing, the stoker engine, or both exterior of the tender water compartment, rearward of the stoker conveyor, above the floor of the water compartment and above the tender base frame in a location where there is ample space to facilitate repairs.

Other objects, advantages and novel details of construction will be apparent during the course 20 of the following description and appended claims taken in connection with the accompanying drawings, in which

Fig. 1 is a vertical longitudinal sectional view 25 of a portion of a locomotive and tender illustrating one form of the invention;

Fig. 2 is a vertical longitudinal sectional view of the rear end of the stoker trough shown in Fig. 1 and illustrates the transmission gearing carried thereby;

30 Fig. 3 is a detail fragmentary sectional view of a portion of the structure illustrated in Fig. 1 showing stoker drive mechanism mounted on the top wall of the tender water compartment;

Fig. 4 is a view similar to Fig. 1 illustrating 35 another form of the invention;

Fig. 5 is a vertical longitudinal sectional view of the rear end of the stoker trough illustrated in Fig. 4 showing the transmission gearing carried thereby;

40 Fig. 6 is a detail fragmentary sectional view of a portion of the structure disclosed in Fig. 4 showing the stoker driving motor mounted at the rear end of the tender;

Fig. 7 is a vertical longitudinal sectional view 45 of a portion of the locomotive and tender and illustrates in detail a part of the drive mechanism for a stoker screw conveyor mounted on the locomotive;

Fig. 8 is a sectional view taken on lines 8—8 50 of Figs. 1 and 4;

Fig. 9 is a sectional view taken on line 9—9 of Fig. 7; and

Fig. 10 is a sectional view taken on lines 10—10 55 of Figs. 1 and 4.

In the drawings, the locomotive tender is des-

ignated generally by the numeral 10 and a portion of the locomotive by 11. The tender body portion is formed with a fuel section or compartment 12 at the forward portion of the tender and a water compartment 13 extending rearward of the fuel compartment separated from each other by the rear slope plate or sheet 14, and side slope sheets 14a, (Fig. 8), fastened at their lower marginal portions to a trough member 15 to form a water tight partition wall. 10

A portion of the tender base or frame, which in the conventional design tender extends from one end of the tender to the other, is shown at 16 coupled at 17 to the locomotive frame 18.

The floor 19 of the fuel compartment is provided with a central longitudinal opening 20 communicating with the trough 15 and through which fuel is supplied to the trough by gravity. Plates 21 are slidably mounted in the opening 20, and may be moved from covering position to 20 permit entry of the fuel into the trough as the supply becomes depleted.

The trough 15 at its forward end opens into a tubular conduit portion 22. A spout member 23 is mounted on the tubular conduit portion 22 to move universally with respect thereto and leads forwardly to deliver fuel to a riser conduit 24 on the locomotive. The riser conduit 24 communicates with the firing opening 25 in the backhead 26 of the locomotive firebox. 30

Suitable mechanism is employed for crushing and for transferring the fuel, including a crushing abutment 27, a conveyor screw 28 mounted in the trough 15 and the tubular conduit portion 22, and a screw 29 in the riser conduit. The crushing abutment 27 is arched over the screw 28 at the forward end thereof for engaging the fuel to crush it to a proper size for firing.

Referring now more particularly to Figs. 1, 2 and 3, the screws 28 and 29 are driven separately at their rear ends through gearing housed in a water tight gear casing 30 by the driving motor 31. The gear casing 30 is carried by the trough and mounted within the water compartment 13. Access may be had to the gear casing 45 from the interior of the water compartment. The motor 31 is mounted exterior of the water compartment on the top wall 32 thereof and rearward of the slope sheet 14 thereby making it easily and conveniently accessible for purposes 50 of inspection, repair and replacement. Bracing 33 prevents the weight of the motor from sagging the top wall 32. The crank shaft of the motor is operatively connected by means of gearing 34 to a downwardly and forwardly inclined 55

drive shaft 35. The drive shaft 35 extends through the water compartment and into the gear casing 30 where it is supported by a bearing 10. The drive shaft is enclosed in a water tight sleeve 36 threaded in the gear casing 30 at its lower end. The sleeve 36 is loosely supported at its upper end in a packing gland 37 and arranged to provide slight telescopic movement therewith. A water tight joint is made between the sleeve 36 and gland 37 by means of packing 38 and an adjustable nut 39. In effect, the parts 37, 38 and 39 form a packing box receiving the sleeve 36.

The transmission gearing in the gear casing 30 for the screw 28 comprises a bevel pinion 40 on the lower end of the drive shaft 35 meshing with a bevel gear 41 on an intermediate stub shaft 42, and a pinion 43 on the intermediate shaft 42 for driving the gear 44 on the screw 28 stub shaft 45, which is secured to and rotates the screw 28 in the stoker trough. Adjacent the bottom of the gear casing is a third stub shaft 46 having a gear 47 thereon in mesh with the pinion 43. A shaft 48 extending longitudinally along the underside of the trough 15 is coupled at 49 to the stub shaft 46. The shaft 48 is enclosed in a water tight sleeve 50. The sleeve 50 at its rear end is threaded in the gear casing 30 and at its forward end is welded at 51 to a transverse wall 52 on the front end of the stoker trough. The shaft 48 is supported vertically at its forward end in a bearing 53. A telescopically extensible shaft 54 is universally jointed exteriorly of the water compartment at 55 to the shaft 48, and at 56 to the rear end of the screw 29 in the riser conduit.

Figures 4, 5 and 6 illustrate an arrangement in which a driving motor compartment 57 is located rearward of the screw 28 and at the rear end of the tender. The compartment 57 is formed in the water compartment shielding the driving motor 68 from the water therein. The compartment 57 comprises front, top and side walls 58, 59 and 60 respectively. The floor 61 of the tender water compartment forms the bottom wall of the motor compartment 57. The motor compartment opens through the exterior rear upright wall 62 of the tender and a removable cover 63 forms its other side wall.

The screws 28 and 29 are rotated through common transmission gearing in a gear casing 64 in a manner similar to that described in regard to the structure shown in Figures 1, 2 and 3, with the exception that a gear 65 on the intermediate stub shaft 42 is driven by a pinion 66 on the forward end of a horizontally disposed drive shaft 67 operatively connected at its rear end to the driving motor 68. The drive shaft 67 extends through the water compartment of the tender and the portion thereof extending through said compartment is housed within a water tight sleeve 69. A water tight joint is provided between the forward end of the sleeve 69 and the gear casing 64, and between the rear end of the sleeve and the front wall 58 of the motor compartment in a manner similar to that described in regard to the sleeve 36 in Figures 1, 2 and 3.

I claim:

1. In combination in a locomotive tender having a base, a body portion with partition walls separating the fuel section from the water section thereof, a conveyor at the bottom of the fuel section mounted to receive fuel therefrom, and a water tight compartment formed in said

water section rearward of said conveyor and opening through an upright wall of the tender, said compartment housing a driving motor for said conveyor.

2. In combination in a locomotive tender having a base, a body portion with partition walls separating the fuel section from the water section thereof, a conveyor at the bottom of the fuel section mounted to receive fuel therefrom, and a compartment rearward of said conveyor for housing the conveyor driving motor, said compartment opening through an upright wall of the tender.

3. The combination in a locomotive tender having a base frame and fuel and water compartments, of a stoker conveyor mounted in said tender beneath the fuel compartment to receive fuel therefrom, stoker drive mechanism mounted above said frame rearward of said conveyor and exteriorly of said water compartment, and means operatively connecting said drive mechanism with said conveyor including a shaft extending through the water compartment.

4. The combination in a locomotive tender having a base frame and fuel and water compartments, of a stoker conveyor mounted in said tender beneath the fuel compartment to receive fuel therefrom, stoker drive mechanism mounted adjacent an exterior wall of the tender above said frame rearward of said conveyor and being shielded from the water in the water compartment, and means operatively connecting said drive mechanism with said conveyor including a shaft disposed in and extending through the water compartment.

5. The combination in a locomotive tender having a base frame and fuel and water compartments, of a stoker conveyor mounted in said tender beneath the fuel compartment to receive fuel therefrom, stoker drive mechanism mounted above said frame rearward of said conveyor and exteriorly of said water compartment, means operatively connecting said drive mechanism with said conveyor including a shaft extending through the water compartment, and a sleeve surrounding that portion of said shaft within the water compartment.

6. The combination in a locomotive tender having a base frame and fuel and water compartments, of a stoker conveyor mounted in said tender beneath the fuel compartment to receive fuel therefrom, said water compartment extending rearwardly of said stoker conveyor, a stoker driving motor mounted adjacent an exterior wall of the tender above said frame rearward of said conveyor, means operatively connecting said motor with said stoker conveyor, said means being disposed in and extending through the water compartment, and a sleeve surrounding that portion of said means within the water compartment.

7. The combination in a locomotive tender having a base frame and fuel and water compartments, of a stoker conveyor mounted in said tender beneath the fuel compartment to receive fuel therefrom, said water compartment extending rearwardly of said stoker conveyor, a stoker driving motor mounted adjacent an exterior wall of the tender above said frame rearward of said conveyor, and means operatively connecting said motor with said stoker conveyor including a shaft disposed in and extending through the water compartment.

8. The combination in a locomotive tender having a base frame and fuel and water compartments, of a conveyor mounted in said tender be-

neath the fuel compartment to receive fuel therefrom, said water compartment extending rearward of said conveyor, drive mechanism mounted on the top wall of said water compartment rearward of said conveyor, and means operatively connecting said drive mechanism with said conveyor including a shaft extending through the water compartment.

9. The combination in a locomotive tender having a base frame and fuel and water compartments, of a conveyor mounted in said tender beneath the fuel compartment to receive fuel therefrom, said water compartment extending rearward of said conveyor, drive mechanism mounted above and rearward of said conveyor, and means operatively connecting said drive mechanism with said conveyor extending through the water compartment.

10. The combination in a locomotive tender having a base frame and fuel and water compartments, of a conveyor mounted in said tender beneath the fuel compartment to receive fuel therefrom, transmission gearing rearward of said conveyor and operatively connected thereto, said water compartment extending rearwardly of said gearing, a drive motor mounted adjacent an exterior wall of the tender above said frame and rearward of said conveyor, and means operatively connecting said drive motor with said gearing including a shaft extending through the water compartment.

11. The combination in a locomotive tender having a base frame and fuel and water compartments, of a conveyor mounted in said tender beneath the fuel compartment to receive fuel therefrom, transmission gearing rearward of said conveyor operatively connected thereto, said gearing being enclosed in a casing to which access can be had from the interior of said water compartment, said water compartment extending rearwardly of said casing, a drive motor mounted above said frame rearward of said conveyor, and means operatively connecting said drive motor with said gearing extending through the water compartment.

12. In combination in a locomotive tender having a base, a body portion with partition walls separating the fuel section from the water section thereof, a conveyor at the bottom of the fuel section mounted to receive fuel therefrom, and a compartment at the rear end of the tender for housing a conveyor driving motor, said compartment opening through an upright wall of the tender.

13. The combination in a locomotive tender having a base frame and fuel and water compartments, of a stoker conveyor mounted in said tender beneath the fuel compartment to receive fuel therefrom, a compartment at the rear end of the tender for housing a conveyor driving motor, means operatively connecting said conveyor including a shaft extending through the water compartment, and a sleeve surrounding that portion of said shaft within the water compartment.

14. The combination in a locomotive tender having a base frame, fuel and water compartments and a conveyor mounted in said tender beneath the fuel compartment to receive fuel therefrom, of transmission gearing rearward of said conveyor and operatively connected thereto, a driving motor mounted adjacent an exterior wall of the tender rearward of said conveyor above said frame and operatively connected to said gearing, and a shaft operatively connected

at its rear end with said gearing extending forwardly therefrom longitudinally of said conveyor and at its forward end being arranged to drive another conveyor.

15. The combination in a locomotive tender having fuel and water compartments separated by partition plates and a fuel trough, and a conveyor mounted in said trough to receive fuel from said fuel compartment of transmission gearing rearward of said conveyor and operatively connected thereto, a driving motor mounted adjacent an exterior wall of the tender rearward of said conveyor and operatively connected to said gearing, a shaft operatively connected at its rear end with said gearing extending forwardly therefrom through the water compartment to the exterior thereof, and a sleeve surrounding that portion of said shaft within the water compartment.

16. The combination in a locomotive tender having a base frame and fuel and water compartments separated by partition plates, a fuel trough beneath the fuel compartment, and a conveyor mounted in said trough to receive fuel from said fuel compartment, of transmission gearing rearward of said conveyor and operatively connected thereto, said gearing being housed within a water tight casing disposed in the water compartment, drive mechanism shielded from the water mounted on the tender adjacent an exterior wall thereof above said frame, rearward of said conveyor and operatively connected to said gearing, a shaft operatively connected at its rear end with said gearing extending forwardly therefrom through the water compartment, and a sleeve surrounding that portion of said shaft within the water compartment.

17. The combination in a locomotive tender having fuel and water compartments and a conveyor mounted in said tender beneath the fuel compartment to receive fuel therefrom, of transmission gearing rearward of said conveyor and operatively connected thereto, said water compartment extending rearward of said conveyor, drive mechanism shielded from the water mounted adjacent an exterior wall of the tender rearward of said conveyor, means operatively connecting said drive mechanism with said gearing including a shaft extending through the water compartment, a sleeve surrounding that portion of said shaft within the water compartment, and a second shaft operatively connected at its rear end with said gearing extending forwardly therefrom longitudinally of said conveyor.

18. The combination in a locomotive tender having fuel and water compartments and a conveyor mounted in said tender beneath the fuel compartment to receive fuel therefrom, of transmission gearing rearward of said conveyor and operatively connected thereto, said water compartment extending rearward of said conveyor, drive mechanism mounted rearward of said conveyor exterior of the water compartment, means operatively connecting said drive mechanism with said gearing including a shaft extending through the water compartment, and a second shaft operatively connected at its rear end with said gearing extending forwardly therefrom longitudinally of said conveyor.

19. The combination in a locomotive tender having a base frame, fuel and water compartments and a conveyor mounted in said tender beneath the fuel compartment to receive fuel therefrom, of transmission gearing rearward of said conveyor and operatively connected thereto, a compartment adjacent an exterior wall of the

5 tender above said frame and rearward of said conveyor for housing a driving motor operatively connected to said gearing, and a shaft operatively connected at its rear end with said gearing extending forwardly therefrom longitudinally of said conveyor.

10 20. The combination in a locomotive tender having a base frame, fuel and water compartments and a conveyor mounted in said tender beneath the fuel compartment to receive fuel therefrom, of transmission gearing rearward of said conveyor and operatively connected thereto, said water compartment extending rearward of said conveyor, drive mechanism mounted adjacent an exterior wall of the tender above said frame rearward of said conveyor and shielded from the water in said water compartment, said drive mechanism being operatively connected to said gearing, and a shaft operatively connected 15 20 at its rear end with said gearing extending forwardly therefrom longitudinally of said conveyor to a point without the water compartment.

25 21. The combination in a locomotive tender having fuel and water compartments and a conveyor mounted in the tender beneath the fuel compartment, of a casing disposed in the water compartment for housing drive mechanism for said conveyor, a sleeve adapted to enclose a drive shaft at one end being fixed with said casing and at its other end being loosely supported on a wall of said water compartment, and means for providing a water tight seal between the loosely supported end of said sleeve and said wall.

30 35 22. The combination in a locomotive tender having fuel and water compartments and a conveyor mounted in the tender beneath the fuel compartment, of a casing disposed in the water compartment for housing drive mechanism for said conveyor, a sleeve adapted to enclose a drive shaft at one end being fixed with said casing and at its other end being loosely supported on a wall of said water compartment, and means comprising a packing box for providing a water tight seal between the loosely supported end of said sleeve and said wall.

40 50 23. The combination of a locomotive tender having fuel and water compartments and a conveyor mounted on the tender beneath the fuel compartment, of a casing disposed in the water compartment, drive mechanism housed in said casing and operatively connected with said conveyor, a sleeve extending through the water compartment at one end being fixed to said casing and at its other end being loosely supported on an exterior wall of said water compartment, a drive shaft housed within said sleeve at one end operatively connected with said drive mechanism and at its other end extending through and beyond the sleeve, and means providing a water tight seal between the loosely supported end of said sleeve and said exterior wall.

55 60 24. In a locomotive tender having a water compartment, the combination of a water tight casing within said compartment, a sleeve extending from said casing through the water compartment to a side wall thereof and opening without said compartment, said sleeve being water tight and at one end rigidly mounted and at its other end loosely mounted, and a packing box receiving said loosely mounted end of the sleeve.

65 70 25. In a locomotive tender having a water compartment, the combination of a water tight casing within said compartment, a sleeve extending from said casing through the water compartment

75 80 85 movement to a wall thereof and opening without said compartment, said sleeve being water tight and at one end rigidly mounted and at its other end loosely mounted, and means receiving said loosely mounted end of the sleeve to form a water tight joint.

90 95 26. In a tender, an underframe, including a rear end portion, superstructure including a tank and a coal hopper equipped with a fuel feeding device, and driving mechanism for said device mounted on said rear end portion and operatively connected with said device.

100 105 27. In a tender, an underframe, a tank thereon, at least a portion of one wall of said tank being disposed inwardly from an adjacent sill of said underframe, a coal hopper located forwardly of said tank and including stoker feeding mechanism, stoker driving mechanism mounted on the exposed portion of said underframe, an elongated housing extending from said inwardly disposed wall of said tank to said coal hopper, and a driving connection for said feeding mechanism extending through said housing.

110 115 28. In a tender, an underframe, a tank thereon, at least a portion of the rear wall of said tank being disposed inwardly from the rear end of said underframe, a coal hopper located forwardly of said tank and including stoker feeding mechanism, stoker driving mechanism mounted on the rear end of said underframe, an elongated housing extending from the end wall of said tank to said coal hopper, and a driving connection for said feeding mechanism extending through said housing.

120 125 29. The combination in a locomotive tender having fuel and water sections, of a conveyor mounted in said tender to receive fuel from said fuel section, gearing housed at the rearward end of said conveyor and operatively connected thereto, a compartment in said water section spaced rearwardly of said gearing and opening through a wall of the tender, a drive motor mounted in said compartment, and means operatively connecting said drive motor with said gearing including a shaft extending through the water section.

130 135 30. The combination in a locomotive tender having fuel and water sections, of a conveyor mounted in said tender to receive fuel from said fuel section, gearing rearward of said conveyor and operatively connected thereto, said gearing being housed within a water-tight casing formed in the water section, a water-tight compartment in said water section spaced rearwardly of said gearing and opening through a wall of the tender, a drive motor mounted in said compartment, means operatively connecting said drive motor with said gearing including a shaft extending through the water section and a water-tight sleeve surrounding that portion of said shaft within the water section.

140 145 31. The combination in a locomotive tender having fuel and water sections separated by partition plates and a fuel trough, and a conveyor mounted in said trough to receive fuel from said fuel section, of transmission gearing housed rearward of said conveyor and operatively connected thereto, a compartment in said water section spaced rearwardly of said gearing and opening through a wall of the tender, a drive motor mounted in said compartment, means operatively connecting said drive motor with said gearing including a shaft extending through the water section, a shaft operatively connected at its rear

end with said gearing extending forwardly therefrom through the water section to the exterior thereof.

32. The combination in a locomotive tender having fuel and water sections, of a conveyor mounted in said tender beneath the fuel section to receive fuel therefrom, said conveyor forming a portion of the top wall of said water section, gear-

ing housed rearward of said conveyor and operatively connected thereto, a compartment in said water section spaced from said gearing, a drive motor mounted in said compartment, means operatively connecting said drive motor with said gearing including a shaft extending through the water section.
